UNITED STATES PATENT OFFICE.

CHARLES SKIDMORE, OF HOMER, NEBRASKA.

WEIGHING-WAGON.

SPECIFICATION forming part of Letters Patent No. 732,228, dated June 30, 1903.

Application filed April 4, 1903. Serial No. 151,147. (No model.)

To all whom it may concern:

Be it known that I, CHARLES SKIDMORE, a citizen of the United States, residing at Homer, in the county of Dakota and State of Nebraska, have invented new and useful Improvements in Weighing-Wagons, of which the following is a specification.

My invention relates to new and useful improvements in weighing-wagons; and its object is to provide scales of novel construction which may be readily attached to wagons of ordinary construction and by the use of which the contents of the wagon may be quickly and accurately determined.

With the above and other objects in view the invention consists in providing rods adapted to be pivotally mounted upon the bolsters of a wagon and each of which has upwardly-extending supporting-plates thereon, upon which the body of the wagon is adapted to rest. Inwardly-extending arms are formed integral with or rigidly secured to the rods, and their inner ends are connected by means of links to opposite sides of a forked plate having hooks which serve to support a pin extending laterally from opposite sides of a scale-beam. The inner end of this beam may be secured in any suitable manner to the sides of the wagon-body.

The invention further consists in the novel construction, combination, and arrangement of the several parts, which will be more fully hereinafter described and claimed, and illustrated in the accompanying drawings, in which--

Figure 1 is a side elevation of a wagon having my improved scales in position thereon; and Fig. 2 is a transverse section through the wagon, the supporting-brackets of the rod being shown in section.

Referring to the figures by numerals of reference, 1 are bolsters of a wagon, to the inner sides of each of which are secured two brackets 2 and 3, respectively, one of which has an eye 4 extending therethrough, while the other is provided with a slot 5, which extends thereto from the upper edge. Mounted in each pair of brackets is a rod 6, having curved plates 7 formed integral therewith or rigidly secured thereto, and these plates are adapted to extend over the bolsters and support the wagon-body 8. An inwardly-extend-

ing arm 9 is secured to one end of each rod 6, and the inner ends of these rods have links 10 pivoted thereto, said links being also pivoted to the upper end of a slotted plate 11. The arms 12, formed by the slot in said plate, are upwardly turned at their lower ends to form hooks 13, which are adapted to receive a pin 14, extending from opposite sides of a scale-beam 15. This scale-beam may be of any suitable length, and the inner end thereof is preferably provided with an oppositely-extending pin 16, which extends into slots 17, formed within parallel ears 18, secured to the side of wagon-body 8. These slots extend into the ears in the lower edges thereof, and the pin is held within them by the weight of the lever.

It will be seen that when material of any kind is placed within the wagon-body the weight thereof will cause the plates 7 to bear downward upon the bolsters 1. To ascertain the weight of the material, an adjustable weight 19 is moved longitudinally upon beam 15 until the body is raised and balanced. When the beam 15 is not in use, it can be readily detached by simply swinging pin 14 upward out of engagement with the hooks 13 and pin 16 downward out of engagement with ears 18. Transversely-extending plates 20 may be arranged upon the body 8 at each end thereof, so as to prevent longitudinal movement of the body in relation to the bolsters 1.

In the foregoing description I have shown the preferred form of my invention; but I do not limit myself thereto, as I am aware that modifications may be made therein without departing from the spirit or sacrificing the advantages thereof, and I therefore reserve the right to make such changes as fairly fall within the scope of my invention.

Having thus described the invention, what is claimed as new is--

1. In a device of the character described, the combination with bolsters; of a plate pivoted to and extending upwardly from each of said bolsters, a wagon-body supported by said plates, arms connected to and movable with the plates, a scale-beam connected to the wagon-body, and a supporting-plate for the beam connected to the arms.

2. In a device of the character described, the combination with the bolsters of a wagon,

of a plate pivoted to each bolster and extending thereabove, a wagon-body supported upon the plates, arms connected to the plates and extending inwardly toward each other, 5 a scale-beam pivoted at one end to the wagon-body, a supporting-plate for said beam at a point intermediate its ends, and link connections between the plate and the arms.

3. In a device of the character described, 10 the combination with bolsters having brackets thereon, of rods journaled within the brackets, plates extending therefrom and above the bolsters, a wagon-body supported upon the plates, arms extending from the rods, a scale- 15 beam pivoted at one end to the wagon-body, a forked supporting-plate, hooks thereon adapted to form a fulcrum for the scale-beam, and link connections between the forked plate and the arms.

4. In a device of the character described, 20 the combination with bolsters having brackets extending therefrom, of rods detachably secured within the brackets, plates extending from the rods and above the bolsters, a wagon- 25 body supported upon the plates, arms secured to and movable with the rods, scale-beam detachably secured at one end to the wagon-body, a forked supporting-plate, hooks upon said plate adapted to form a fulcrum for the scale-beam, and link connections be- 30 tween said plate and the arms.

In testimony whereof I affix my signature in presence of two witnesses.

CHARLES SKIDMORE.
